UNITED STATES PATENT OFFICE.

GEORGE LOUIS BUFF, OF BOSTON, MASSACHUSETTS.

DESIGN FOR A VERNIER-PLATE FOR SURVEYING INSTRUMENTS.

SPECIFICATION forming part of Design No. 33,545, dated November 13, 1900.

Application filed August 25, 1900. Serial No. 28,077. Term of patent 7 years.

To all whom it may concern:

Be it known that I, GEORGE LOUIS BUFF, a citizen of the United States, and a resident of Boston, in the county of Suffolk and State of Massachusetts, have invented and produced a new and original Design for a Vernier-Plate for Surveying Instruments, of which the following is a full, clear, and exact description.

Reference is to be had to the accompanying drawings, forming a part of this specification, in which similar characters of reference indicate corresponding parts in both the figures.

Figure 1 is a plan of a vernier-plate embodying my design; and Fig. 2 is a front elevation thereof.

The leading feature of my design consists in a vernier-plate having a bubble-tube disposed near the edge thereof, arms rising from the plate at one end of said tube, and a curved finger rising from the plate at the other end of the tube and extending over the latter.

As shown in the drawings, A is the vernier-plate, having the two verniers A' A² at its periphery and at its center a projecting compass-ring A³, on top of which is located the

pane B. A bubble-tube G is arranged upon the upper surface of the plate A and extends approximately at a tangent to the ring A³. At one end of said tube, near the edge of the plate A, parallel arms H rise from said plate on opposite sides of said end. These arms and the stud H', which supports the outer end of the bubble-tube, constitute a single piece of metal of the form shown in Fig. 2. At the other end of the tube G a curved finger I rises from the plate A and extends partly over the tube. A similar finger I' is located at a diametrically opposite point of the plate A.

Having thus described my invention, I claim as new and desire to secure by Letters Patent—

The design for a vernier-plate for surveying instruments, as herein shown and described.

In testimony whereof I have signed my name to this specification in the presence of two subscribing witnesses.

GEORGE LOUIS BUFF.
